US00D910078S

(12) **United States Design Patent** (10) Patent No.: **US D910,078 S**
Dill et al. (45) Date of Patent: **** Feb. 9, 2021**

(54) **DISPLAY DEVICE WITH GRAPHICAL USER INTERFACE**

- (71) Applicant: **Lyft, Inc.**, San Francisco, CA (US)
(72) Inventors: **Katherine Marisa Dill**, San Francisco, CA (US); **Daniel Lami Goldstein**, Berkeley, CA (US); **Jisi Guo**, San Francisco, CA (US); **Dor Levi**, San Francisco, CA (US); **Robert Joseph Marsan**, San Francisco, CA (US); **Steven James Martisauskas**, San Francisco, CA (US); **Meghan Elizabeth Robichaud**, San Francisco, CA (US); **Jean-Pierre Simard**, San Francisco, CA (US); **Christine Mara Todorovich**, San Francisco, CA (US); **Carlos Ellis Whitt**, San Francisco, CA (US)
(73) Assignee: **Lyft, Inc.**, San Francisco, CA (US)
(**) Term: **15 Years**
(21) Appl. No.: **29/738,686**
(22) Filed: **Jun. 18, 2020**

Primary Examiner — Daniel J Domino(74) *Attorney, Agent, or Firm* — Haynes and Boone, LLP**CLAIM**

The ornamental design for a display device with graphical user interface, as shown and described.

DESCRIPTION

The FIGURE is a front view of a display device with graphical user interface.

The broken lines are included for the purpose of showing environmental portions of the display device with graphical user interface and form no part of the claimed design.
